TRANSMISSION LINE

Martin Katzin and Ferdinand J. W. Schoenborn,
Riverhead, N. Y., assignors to Radio Corporation of America, a corporation of Delaware

Application September 12, 1940, Serial No. 356,424

1 Claim. (Cl. 174—27)

The present invention relates to transmission lines for use at radio frequencies, and particularly to such lines which are provided with terminal or end fittings for maintaining the overall lengths of the conductors of the line equal.

In the design and installation of concentric transmission lines exposed to external temperature changes, it is usually necessary to provide means to allow for differential expansion and contraction between the lengths of the inner and outer conductors of the line due to the transient differences of temperature between these conductors caused by varying ambient temperature. Known means for accomplishing this result include sliding contact sleeves, flexible bellows or diaphragms, or combinations of these or related devices. The use of such known arrangements is undesirable, particularly at ultra high frequencies, for several reasons. Sliding contacts are prone to introduce noise when used in receiving circuits, thus requiring maintenance to keep the contacting surfaces clean. Flexible bellows and diaphragms introduce lumped changes in the electrical constants of the line at very high frequencies, and the expansion and contraction of these devices further results in changes in the electrical properties of the line, which produce undesirable reflections of the electric wave energy.

The present invention is primarily concerned with high frequency transmission lines having terminal or end fittings for maintaining the overall lengths of the conductors of the line equal, and has for its principal object to prevent the setting up of undue mechanical stress on the terminal fittings of the line caused by changing ambient temperature, without the provision of sliding contacts or expansion members. In accordance with the present invention, the temperature difference between the inner and outer conductors of a concentric transmission line is kept low by introducing a time lag in the change of ambient temperature around the outer pipe or conductor. By making this time lag of the order of or greater than the time required for the temperature of the inner conductor to come to that of the outer conductor when the latter is given a sudden temperature change, there will be very little temperature difference between the two conductors. If the maximum temperature difference between inner and outer conductors is held to a few degrees, it will usually be possible to provide rigid terminal fittings which will safely stand the resulting mechanical stresses. By constructing the concentric line in

accordance with the invention, there is avoided the necessity for providing means to allow for differential expansion of the inner and outer conductors.

5 To introduce the desired time lag between the change in ambient temperature and that of the outer conductor, it is only necessary, in accordance with one embodiment of the invention, to provide an adequate amount of heat insulation on the outer conductor. Any heat insulating material or combination of such may be used. A few possible materials are standard asbestos air-cell sleeving as used on heat pipes, bituminous mastic coating, alternate layers of two or more different heat insulating materials, such as heavy cloth and bituminous tape, asbestos sheet and heavy cloth, insulating sheeting covered with bituminous mastic, etc. This insulation may take any desired form. It may conveniently be applied in the form of a spiral tape of heat insulating material wrapped over the outer conductor, or be built up of a number of such spirals, of the same or different materials. The insulation may also take the form of split 10 sleeves slipped over the outer pipe and then fastened in place.

Data on the amount of time lag which a given insulating treatment will provide may be obtained by calculation, or by experiment, consideration to be given, of course, to the thermal capacity of the inner and outer conductors of the transmission line, the spacing and the type of dielectric therebetween. In practice, resort to experimental results would probably be made.

35 The amount of time lag required does not depend on the ambient temperature itself (that is, on whether the weather is very hot or very cold), but on the rapidity with which the ambient temperature changes. The primary concern of 40 the present invention is to keep the temperature difference between the inner and outer conductors of the transmission line very low, such that the overall lengths of the inner and outer conductors are maintained equal to each other as far as possible.

Another embodiment of the invention involves enclosing the concentric line in a third pipe which is larger than the outer conductor of the line.

45 The accompanying drawing illustrates three embodiments of the invention given by way of example only, wherein:

Fig. 1 shows a concentric line provided with heat insulating material surrounding the outer conductor;

Fig. 2 shows the concentric line enclosed by a third larger pipe suitably spaced from the outer conductor of the line; and

Fig. 3 shows the principles of the invention applied to a balanced twin-conductor line.

In these figures, the same parts are represented by the same reference numerals.

Referring to Fig. 1 of the drawing, an ultra high frequency concentric conductor transmission system is schematically indicated as comprising an outer tubular conductor 2, with an inner tubular conductor 1 arranged in the interior thereof and concentrically therewith. The two conductors are maintained in proper spaced relation by means of suitable insulating washers or spacers 3 spaced at suitable intervals and preferably these washers have openings or slots through them to permit the circulation of air in the spaces between the conductors. These spacers may have any suitable form or shape. The outer conductor 2 is shown surrounded by heat insulating material 4 such as heavy cloth, felt, asbestos, asbestos-air-cell sleeving, etc. applied in the form of sleeving or, if desired, spiral-wound tape or sheeting. Surrounding layer 4 there is provided an outer layer of heat insulating material 5 which may be a suitable material combining heat insulating and weather proofing properties. If desired, layer 5 may be a heavy layer of bituminous mastic which serves the dual purpose of heat insulating and weather proofing the outer conductor. The heat insulating properties of the layers 4 and 5 are of such thickness and have such characteristics as to maintain the temperature difference between the conductors 1 and 2 of the concentric transmission line as low as possible. In selecting the heat insulating materials, consideration is given to the thermal capacities of the conductors 1 and 2 and to the design, location and construction of the concentric line. Obviously the two layers 4 and 5 surrounding the outer conductor may be replaced by a single layer having the desired heat insulating qualities and whose thickness is so calculated as to introduce the desired time lag in the change of ambient temperature around the outer pipe or conductor.

The rigid terminal or end fittings for the concentric line have not been shown since they do not form part of the present invention per se, except in combination with the arrangements disclosed for introducing a time lag in the change of ambient temperature around the line. These fittings may, if desired, be of the type described in the copending application of Harold O. Petersen, Serial No. 310,807, filed December 23, 1939, now United States Patent No. 2,331,136, granted October 5, 1943, which rigidly terminates the ends of a concentric line and prevents sliding of the inner conductor relative to the outer conductor.

In one experimental embodiment of a concentric transmission line of the type shown in Fig. 1 and tried out in practice, the outer conductor was a copper pipe of 3 inches inner diameter and 3.13 inches outer diameter; the inner conductor was a copper tube of $\frac{7}{8}$ inch outer diameter; the heat insulating layer 4 was a closely wound spiral wrap of 4 inch wide burlap upholstery webbing having no overlap; while insulating layer 5 was a reverse overlapping spiral wrap of 2 inch wide friction tape. Tests taken on such a line over an extended period of time indicated that the extreme temperature difference between inner and outer conductors was 4° C.

In another experimental embodiment of a con-

centric transmission line arrangement like Fig. 1 tried out in practice, the heat insulating layer 4 was a layer of 45 ounce hair felt applied in the form of split sleeving, and layer 5 was an overlapping spiral of 2 inch friction tape, the whole covered with several coats of asphaltum varnish. This arrangement gave appreciably better results than the preceding scheme tried out in practice, in holding down the temperature difference between the two conductors of the line.

Fig. 2 illustrates another embodiment of the invention in which the concentric line 1, 2 is surrounded by a third larger pipe 6, the latter being spaced from the outer conductor 2 by means of suitable dielectric spacers 7. Conductor 6 need not be made of copper but may be made of any suitable inexpensive material. Spacers 7 are star-shaped or provided with vents to decrease the amount of solid dielectric between pipe 6 and conductor 2. It is preferred, though not essential, that the space between conductor 2 and pipe 6 be evacuated to reduce heat transfer across this space. Furthermore, the facing surfaces of the conductor 2 and pipe 6 may be silver coated or provided with any bright finish to reduce the coefficient of heat emission. Such an arrangement would, in effect, make of the described arrangement a Dewar or vacuum flask with its attendant heat-insulating properties. If desired, insulating material may be added about the third pipe 6 to improve the heat insulation of the system. This latter measure may be combined with the vacuum flask idea, or it may be used without provision for evacuation of the space between the outer conductor and the third pipe. Of course, end or terminal fittings are provided for the pipe 6 as well as for the conductors 1, 2 of the concentric line.

Fig. 3 illustrates the application of the invention to a balanced twin-conductor line comprising parallel conductors 1', 1'. These conductors are surrounded by an outer conductor 2' and spaced therefrom as well as from each other by suitable dielectric spacers 3'. Around the outer conductor 2' are provided the heat insulating layers 4 and 5 in the manner described above in connection with Fig. 1. As in the case of Figs. 1 and 2, the end fittings for the conductors 1', 1' and 2' are not shown.

The term "parallel conductors" used in the appended claims is deemed to include a two-transmission line whether made of wires or of coaxial conductors.

What is claimed is:

A high frequency transmission line system comprising a pair of parallel conductors whose relative lengths are to be maintained substantially equal for all temperature conditions, said conductors being inflexible and rigidly supported, spacers of dielectric material between said conductors for maintaining constant spacing between the conductors, thermal insulation surrounding said conductors for preventing sudden temperature changes in the conductors to thereby maintain at all times a low temperature difference between said conductors, the thickness of said insulation being such as to maintain a low temperature difference between said conductors within predetermined limits in the presence of appreciably higher ambient temperature changes, and rigid terminals at both ends of said line to prevent sliding of one conductor relative to the other conductor.
